his Atty.

UNITED STATES PATENT OFFICE.

JULIUS O. JACOT, OF STOCKBRIDGE, MASSACHUSETTS.

DESIGN FOR A WATCH-DIAL.

SPECIFICATION forming part of Design No. 24,689, dated September 24, 1895.

Application filed December 29, 1894. Serial No. 533,351. Term of patent 3½ years.

To all whom it may concern:

Be it known that I, JULIUS O. JACOT, a resident of Stockbridge, in the county of Berkshire and State of Massachusetts, have invented a new and useful Design for a Watch-Face, of which the following, taken in connection with the accompanying drawings, is a specification.

Figure 1 is a plan view of the watch-dial. Fig. 2 is a sectional view of the same.

10 The leading feature of my design consists in raised dots A, arranged in a circumference of radial points with raised dots B B, one on each side of the radial points at regular intervals, and a raised bar C at each quarter of 15 the circumference across the line of radial points, all within the contour of the dial-plate.

A minor feature is the circular opening D in the center.

Having described my invention, what I claim, and desire to secure by Letters Patent, is—

The design for a watch dial or face herein shown and described.

In testimony whereof I have signed my name to this specification, in the presence of 25 two subscribing witnesses, on this 13th day of December, A. D. 1894.

JULIUS O. JACOT.

Witnesses:

H. DUNHAM,
CYRUS F. WILLARD.
